[57] CLAIM

The ornamental design for ski goggle lens tester, as shown and described.

DESCRIPTION

FIG. 1 is a front elevational view of a ski goggle lens tester showing my new design;

FIG. 2 is a top plan view;

FIG. 3 is a left side elevational view;

FIG. 4 is a rear elevational view;

FIG. 5 is a bottom plan view;

FIG. 6 is a left side elevational view, shown with the glare-reducing lens element in raised position;

FIG. 7 is a front elevational view, shown with the glare-reducing lens element in raised position; and,

FIG. 8 is a perspective view thereof.

FIGS. 4-7 have been drawn to a reduced scale with respect to FIG. 1 thereof.

FIG. 1

FIG. 2

FIG. 3

FIG. 4

FIG. 5

FIG. 7

FIG. 6

FIG. 8
